John Darock

United States Patent Office.

JOHN DAVOCK, OF NEW YORK, N. Y.

Letters Patent No. 60,702, dated January 1, 1867.

IMPROVEMENT IN WOOD-SPLITTING MACHINES.

The Schedule referred to in these Letters Patent and making part of the same.

I, JOHN DAVOCK, of No. 788 Eleventh Avenue, in the city, county, and State of New York, have invented a new and useful Improvement in Wood-Chopping Machines; and I do hereby declare that the following is a full, clear, and exact description of the same, reference being had to the accompanying drawings, forming part of this specification, in which—

Figure 1 is a front elevation of the machine.

Figure 2 is a vertical section through the lines A B and C D.

Similar letters of reference indicate corresponding parts in the two figures.

This invention consists principally in attaching the knife or knives to a rotary spindle, which works in a cross-head, moving between slides up and down in vertical direction. It also consists in a novel arrangement of providing for the shoving down of the wood from the knife. It also consists in the combination, with the cross-head, of a lever, rack, and wheel to give the requisite rotary motion to the spindle and the knife or knives. It further consists in an improved feeding arrangement, in order to save the belt which is used for carrying the wood into the machine from destruction, hereinafter described. It also consists in a certain device for the purpose of changing the depth of the stroke of the knife or knives without altering the stroke of the crank, as hereinafter described.

To enable others skilled in the art to make and apply my invention, I will proceed to describe its construction and operation.

A^X A^X represent a stout frame of wood or other suitable material, to which the different parts of the machine are attached. B^X is a single crank-shaft, provided with driving pulley C^X, fly-wheel D^X, and connecting-rod E, which is attached at a to the cross-head F, in order to give the required vertical reciprocating motion to said cross-head. There are also two slide pieces, b b', fastened to the inner side of the frame to serve as a guide for the motion of the cross-head. This cross-head is made open in order to give room for the wheels o o¹ and fast collar d, on the rotary spindle G; also for the horizontal reciprocating motion of the rack e and its connecting-rod, f. This rod, f, is attached to the rack e at g, and at h to the lever H, which is of suitable shape, and has its fulcrum at h' in a joint on top of the cross-head F. The lever H is also provided with a slot on one end to receive the connecting-pin i of the rod f, in order to change the stroke of the rack e. The rod f is also provided on both ends with different holes in order to lengthen or shorten the rod f for the same purpose. The cross-head F is bored out to receive the rotary spindle G, which is shown by dotted lines in the drawing, and has a suitable-shaped plate, K, on its lower end for the purpose of fastening the knife Z, or any desired number of knives, in any desired position to said spindle. There are also two collars on that spindle; one of them, marked d, is secured by means of a taper pin, m, to said spindle in order to support the weight of the rotary spindle with the attached knife or knives, therefore allowing the wheels and rack to be moved easier than it could be done if the collar d would be loose on said spindle. The other collar, d¹, turns loose on the spindle G, between the lower face of the cross-head and the plate K, and is considerably longer than collar d, as shown in the drawing. Now, in order to change the depth of the stroke of the knife or knives, the spindle G has to be taken out of the cross-head, and the relative position of the two collars changed, so that collar d¹ would come in place of collar d. The lower collar, d¹, is also provided with a corresponding hole for the taper pin m, in order to secure said collar to the spindle G for the purpose already described. K¹ represents an adjustable guide for the rack e. It is also provided with a slot in order to raise it to a corresponding height after the changing of said collars. A screw, n, secures it to the cross-head. On top of the collar d is a small toothed wheel, o¹, which is keyed to the spindle G. There is also a larger toothed wheel, o, on top of it, to which is attached a suitable spring, p, and catch, p¹, which works into the toothed wheel o¹ in order to produce the required rotary motion of the spindle G. The wheel o turns loose on the spindle, and is moved by the horizontal reciprocating motion of the rack e. The connection of the rod f with the rack e and lever H is already described. There is also attached to the frame A an adjustable rod, q, and pin, q¹. Now, in the upward motion of the cross-head, the end, r, of the lever H strikes against the rod q and forces the other end of the lever up, and consequently the attached rod f follows, draws the rack forward a certain distance, and turns the loose wheel o also. The motion of this wheel acts upon the spring p, and causes the latch p¹, which works in the toothed wheel o¹, to turn the same a corresponding distance. Now, as the wheel o¹ is keyed to the spindle, consequently the spindle and knife will

be turned also, say about a quarter of a revolution each time. In the downward motion of the cross-head the end, r , of the lever H will strike against the pin q^1 , forces the other end of the lever down, and moves the rack e back to its former position without turning the spindle or knife. The cross-head F is also provided with three or more cams, marked s , s^1 , etc. A short rod, t , runs through the plate, K , of the spindle G ; having a square plate, u , on the lower, and a head, u^1 , on the upper side. A spring, v , works between the head and the plate. Now, when the spindle G and plate K revolve, the rod t strikes against the inclined planes, $\times \times$, of the cams s , s^1 , etc., and is forced down in order to relieve the knife Z from the wood. L represents the chopping plate or table to split the wood on. It is made of iron, and fastened to the frame A . $M M^1$ are two feed rollers with a belt, y , around them in order to feed the blocks of wood into the machine. Those blocks are placed on top of the belt. The main improvement in this feeding arrangement is to run the belt y off in front of the table L , so that it cannot be injured or destroyed by chopping the wood on top of it, as is the case in other machines. The arrangement for turning the feed rollers $M M^1$ is similar to that employed in turning the spindle G , and will be easily understood by the drawing. A vertical rack, N , works inside of the frame A , and is raised by a lug or pin, v , secured to the cross-head F . The downward motion of the rack N is produced by its own weight. This rack works into a toothed wheel, w^1 , which turns another one, w , of similar size, loose on the shaft of the roller M . A smaller toothed wheel, z , is keyed to said shaft, and is turned by a latch, x^1 , attached to the loose wheel w , in the same way as already described. The side board $N^2 N^2$ serves as a guide or channel for the wood to be fed into the machine.

What I claim as my invention, and desire to secure by Letters Patent, is—

1. The rotary spindle G with the attached knife Z ; or knives, in combination with the cross-head F , arranged substantially as herein shown and described.
2. In combination with the rotary spindle G , I claim the vertically sliding rod t , operated by the cams s , s^1 , etc., substantially as for the purpose herein specified.
3. The combination of the cross-head F with the lever H , rack e , connecting-rod f , and toothed wheels o , o^1 , the whole being arranged and operating substantially as and for the purpose herein set forth.
4. I claim the arrangement and combination of the feed rollers $M M^1$, endless belt y , gear-wheels w , w^1 , rack N , and pin v , the whole being arranged and operating substantially as and for the purpose herein specified.

JOHN DAVOCK.
